Inventor:

UNITED STATES PATENT OFFICE.

EUGENIO K. HAYES, OF GALVA, ILLINOIS.

HAND-CART.

SPECIFICATION forming part of Letters Patent No. 627,261, dated June 20, 1899.

Application filed September 24, 1898. Serial No. 691,750. (No model.)

To all whom it may concern:

Be it known that I, EUGENIO K. HAYES, a citizen of the United States, residing at Galva, Illinois, have invented certain new and useful Improvements in Hand-Carts, of which the following is a specification.

In the drawings, Figure 1 is a side elevation of my improved hand-cart with a portion of the side of the box broken away at the rear. Fig. 2 is a transverse section taken in the line 2 of Fig. 1. Fig. 3 is an end elevation of a section taken in line 3 of Fig. 1, showing a portion of the end board of the box. Fig. 4 is a perspective view showing one of the brackets arranged in the corners of the box to receive the end boards; and Fig. 5 is a perspective view of an end of one of the end boards of the box.

In making my improved cart I take wheels A of the desired size and mount them on an axle B. I arrange on the axle, near the hubs of the wheels, clips C, in which the shafts or handles c are arranged. These clips have studs or pins D extending up a desired distance above the axle, and around which coiled springs d are arranged. The box E of the cart is provided with a cross-piece e, having holes in its ends outside of the sides of the box, adapted to be passed over the tops of the studs D and to rest upon the springs d. The shafts or handles c incline upward, as shown in Fig. 1, and provide supports for the front end of the box. When in use, the handles are held at about the proper elevation to make the box level from its front to its rear end.

The box of the cart is made with a bottom, side boards, and end pieces. The side boards E' are attached to the bottom and held in an upright position therefrom, preferably by straps e', extending up from the cross-piece e. To further maintain them in their upright position against internal pressure when loaded and to permit of the end pieces E' being securely inserted in place, so as to withstand internal pressure, I arrange on the side boards of the box corner-brackets F. These corner-brackets are preferably cast and attached to the side boards by screws or rivets, as may be desired. They are provided with a flange f, extending inwardly, as shown in Fig. 4.

They are also provided with a notch f' at their upper ends and with a hole f² near their lower ends and with a lug f³ on the flange f. All these parts will be readily understood from an inspection of Fig. 4 and need not be further described in detail. The ends of the end boards are also provided with corner-brackets G, which may be cast and screwed or riveted in place on the end boards. They are provided with a button or headed pin g near the top and a notch g' near the bottom. In addition to this a pivoted locking-plate g² is attached to the outside of the bracket. All these details will be readily understood from an inspection of Fig. 5 and need not be further explained. In order to insert the end boards and lock them in place, so as to be securely united to and with the side boards of the box, I take the end board and slip it down into place, with the lower edge sufficiently out to escape the stud f³, until the head of the headed pin g is received into the recess f'. I then push the bottom of the end board in, so that the notch g' rests over the lug f³. I then turn the locking-plate g² until its locking end passes into the hole f². This securely fastens the end board and the side boards of the box together. It cannot be pushed out to the rear, because the headed pin g and the locking-plate g² prevent. It cannot be slid up without removing the locking-plate g² from the hole f², because the lug f³ prevents. The side boards cannot be pushed out or away from the ends of the end boards, because the headed pins g², caught or received into the recess f', prevent. Thus it will be seen that the side boards and end boards of the box are securely caught, attached, and held together against internal pressure exerted against the sides or the ends of the box from within when loaded.

What I regard as new, and desire to secure by Letters Patent, is—

1. The combination of wheels, an axle, clips arranged on the axle, shafts or handles arranged in the clips, studs rising above the axle from the clips, coiled springs arranged around the studs, and a box resting upon the springs, substantially as described.

2. The combination of side boards, corner-

brackets arranged on the side boards, each provided with an inwardly-extending flange and with a notch at its upper end and with a hole at its lower end and with a lug on the flange, and end pieces provided with corner-brackets each provided with a headed pin or stud near its top and with a notch on its in-

ner side near its bottom and with a locking-plate, substantially as described.

EUGENIO K. HAYES.
